UNITED STATES PATENT OFFICE.

JAMES F. MUNSIE, OF BROOKLYN, ASSIGNOR TO THOMAS L. COLES, OF NEW YORK, N. Y.

INSULATOR.

SPECIFICATION forming part of Letters Patent No. 426,203, dated April 22, 1890.

Application filed January 17, 1890. Serial No. 337,247. (No model.)

To all whom it may concern:

Be it known that I, JAMES F. MUNSIE, a British subject, residing at Brooklyn, in the county of Kings and State of New York, have 5 invented certain new and useful Improvements in Overhead or Air-Line Systems of Electrical Conductors; and I do hereby declare the following to be a full, clear, and exact description of the invention, such as will 10 enable others skilled in the art to which it appertains to make and use the same.

My invention relates to certain new and useful improvements in overhead or air-line systems of electrical conductors, and particularly 15 in the means employed for attaching said conductors to their points of suspension, such as the cross-arms of posts and the like.

The object of the invention is to furnish as 20 an efficient substitute for the "insulators" ordinarily employed for this purpose a device that will render it unnecessary to bend or twist the wire at the point of attachment, (thereby tending to injure the insulating coating or covering upon the wire,) but which will 25 clasp or bind upon a straight section of the wire with sufficient clamping force to attach it rigidly to the desired suspension-point and without injury to the wire covering, the entire apparatus being of a simple, cheap, and 30 durable construction, adapted to be readily manipulated by linemen of ordinary skill.

The construction shown herein embodies 35 certain generic features shown in my application for Letters Patent, Serial No. 328,594, filed October 29, 1889, and constitutes an improvement upon the device shown in said application.

In the accompanying drawings, Figure 1 represents in side elevation a portion of a 40 supporting-pole provided with my improvements. Fig. 2 represents, on an enlarged scale, a cross-section taken on the line 2 2 of Fig. 1. Fig. 3 represents, also on an enlarged scale, an end view of one of the clamping-sleeves. Fig. 45 4 represents a vertical central longitudinal section through the entire device. Fig. 5 represents a horizontal central longitudinal section of the same; and Fig. 6 represents a bottom plan view of the upper cap-piece before 50 the sleeves have been applied, the rubber lining being shown as broken away.

Similar numerals of reference indicate similar parts throughout the several views.

Referring to the drawings, 7 indicates a pole or standard provided on opposite sides with 55 the cross-arms 8 9. To these cross-arms is screwed, nailed, or otherwise rigidly connected a wire-supporting piece or bed-piece 10, constituting one of the elements of my invention. This bed-piece 10 is provided with a central 60 longitudinal groove or depression lined with sheet-rubber 11 or its equivalent, and at its middle portion beneath the rubber there is cut into the wood a series of cross-indentations 12, forming a partial screw-thread, into 65 which the rubber is adapted to be passed by the clamping operation. At its opposite ends 13 14 the bed-piece 10 is tapered off conically. Surmounting the bed-piece 10 is a similar 70 cap-piece 15, having a corresponding longitudinal groove 16, rubber lining 17, middle screw-thread indentations 18, and conical ends 19 20. The rubber-lined grooves of the two pieces are of such shape as to receive between them the insulated conductor or line-wire 21. 75

The means employed for forcing the cap-piece 15 toward the bed-piece 10, so as to clamp and hold the line-wire 21 between them, consist of the clamping-sleeves 22. These clamping-sleeves are provided with an 80 internal conical screw-thread at the end adjacent to the pieces 10 15, and their opposite ends are bell-mouthed so as to permit the line-wire to sway with the wind without coming in contact with the inner walls of the 85 bell-mouth.

The clamping-sleeves are preferably of hard wood, as oak, and the pieces 10 15 of softer wood, such as yellow or white cedar, and the conical ends of the pieces 10 15 are 90 preferably without a screw-thread when put in place. This construction enables the hard-wood clamping-sleeves to cut their own thread upon the softer conical ends of the pieces 10 15, thereby insuring a substantial 95 and satisfactory joint. At their under portions the clamping-sleeves are slotted, as indicated at 23, so as to permit them to pass over the line-wire.

The mode of operation is as follows: The 100 bed-piece 10 is first secured to the cross-pieces 8 9, and the line-wire is then stretched along

the piece 10 so as to rest upon the rubber lining of the longitudinal groove therein. The cap-piece 15 is then superimposed upon the line-wire and held in place until the 5 clamping-sleeves 22 are screwed on. These clamping-sleeves gradually force the cap-piece 15 with constantly-increasing clamping effect upon the line-wire 21, binding it firmly and rigidly within the longitudinal grooves 10 and forcing the rubber lining into the screw-thread indentations 12 18, so that the subsequent end strain upon said linings, due to the weight of the suspended wire, shall not be able to pull said linings out of the grooves. The 15 clamping-sleeves are screwed up until the binding action is sufficient, compensating washers, as 24, being provided, if needful. After the clamping-sleeves are screwed on the spaces left along each side of the rubber 20 lining between the pieces 10 15 are filled in with tar-yarn, mastic, or other suitable filling that will protect the edges of the rubber from atmospheric influences.

The line-wire may be readily released at 25 any time, should occasion require, by merely unscrewing the clamping-sleeves.

It is of course evident that if desired I may employ as a substitute for the rubber lining any other lining of a sufficiently elastic and 30 flexible character, such as tar-yarn, light felt or the like, although for most purposes I find the employment of rubber the more advantageous.

Having thus described my invention, what I 35 claim, and desire to secure by Letters Patent, is—

1. In an overhead or air-line system of electrical conductors, the combination, with a supporting-piece or bed-piece for the line-wire, of 40 a cap-piece therefor, both of said pieces having tapering ends, and internally-screw-threaded clamping-sleeves fitting over said ends and adapted to draw the cap-piece down toward the bed-piece, so as to clamp the line-wire between them, said clamping-sleeves being of harder material than the tapering ends, so as to cut a screw-thread upon the latter during the clamping operation, substantially 45 as described.
2. In an overhead or air-line system of electrical conductors, the combination, with a supporting-piece or bed-piece having a longitudinal groove provided with a flexible or elastic

lining for the reception of the line-wire, of a cap-piece of like construction, both of said pieces having tapering ends, and internally-screw-threaded clamping-sleeves fitting over 55 said ends and adapted to draw the cap-piece down toward the bed-piece, so as to clamp the line-wire between them, substantially as described.

3. In an overhead or air-line system of electrical conductors, the combination, with a supporting-piece or bed-piece having a longitudinal groove provided with a flexible or elastic 60 lining for the reception of the line-wire and with cross-indentations back of said lining, of a cap-piece of like construction, both of said pieces having tapering ends, and internally-screw-threaded clamping-sleeves fitting 65 over said ends and adapted to draw the cap-piece down toward the bed-piece, so as to clamp the line-wire between them, substantially as described.

4. In an overhead or air-line system of electrical conductors, the combination, with a supporting-piece or bed-piece having a longitudinal groove provided with a flexible or elastic lining for the reception of the line-wire, of a cap-piece of like construction, both of said 70 pieces having tapering ends, and internally-screw-threaded clamping-sleeves fitting over said ends and adapted to draw the cap-piece down toward the bed-piece, so as to clamp the line-wire between them, substantially as described.

5. In an overhead system of electrical conductors, the combination, with a supporting-piece or bed-piece for the line-wire, of a cap-piece therefor, both of said pieces being made 75 of soft wood and having tapering ends, and internally-screw-threaded clamping-sleeves of harder material adapted to cut screw-threads 80 upon said tapering ends and to draw the cap-piece down upon the bed-piece, so as to clamp the line-wire between them, substantially as described.

In testimony whereof I affix my signature 85 in presence of two witnesses.

JAMES F. MUNSIE.
